PACKAGE-BINDING IMPLEMENT.

Application filed September 30, 1922. Serial No. 591,477.

This invention is a package binding mechanism of the portable type adapted to be positioned at will on an ordinary package for the performance of the operations 5 of applying a binding wire tightly to said package, and of fastening or locking said binding wire in the required tight relation to said package.

A portable machine for the specified purposes requires that the operating parts be capable of easy and rapid operation and without demanding unusual or laborious effort on the part of the workman; that the binding wire be introduced with ease and 15 facility, and that said wire be held securely against slipping in the operation of tensioning said wire, and that said wire be quickly disengaged from the machine following the operations of applying and securing said 20 wire; that in tensioning the wire it must be drawn tightly into contact with the package, or, in effect, that said wire shall be embedded in the material at the corners of the package, to the end that the wire 25 presses or binds the package, so as to compensate for shrinkage of the wood, and so as to retain the wire from slipping off the package in case the wood shrinks to an appreciable extent; that the end portions of 30 the wire be fastened securely together while said wire is under tension, and that the machine may be easily and quickly removed from the engagement with the wire and dismounted from the package.

In the invention it is sought to provide a machine which meets the foregoing requirements by a simple construction which is efficient in operation and is manipulated with minimum labor and effort by the work- 40 man.

One part of the invention is a retaining member constituting an element of a tensioning means, said member being cooperable with a previously shouldered wire for 45 holding the latter against slipping during the tensioning operation, and said member being controllable for the rapid release of the wire subsequently to the wire tensioning and fastening operations.

It is to be understood that we do not employ a straight length of wire and deform it after its introduction into the machine, but the present invention is designed to act

upon a wire previously deformed, the retaining member receiving the deformation 55 of such previously-deformed wire in a manner to anchor or hold such wire against slipping during the tensioning operation, and said retaining member operating to release the deformed part of the wire subsequently 60 to the tensioning operation and the twisting operation, thus precluding wedging of the shouldered or deformed part of the wire within the retaining member and facilitating the ready dislodgment of the implement 65 or tool from the tied wire. In the present construction we dispense with any part having a tendency to deform the wire and make the retaining member the sole means of anchoring or retaining the wire against slipping under tension. 70

The retaining member is non-deformable, that is, it does not in any way change the form or character of the wire used in the machine. Its only function is to anchor or hold a wire which prior to its introduction or use in the machine has been deformed, in one way or another, to produce a shoulder 75 acting as an abutment in conjunction with the retaining member as the sole means of effecting such anchorage. In one acceptable form the abutting faces of the deformed part of the wire and the retaining member are substantially rightangled to the line of pull to insure efficient anchorage 80 without the employment of extraneous means for this purpose.

Another part of the invention is an operating means for applying power to said tension head, the same embodying a shaft for 90 carrying said head, a worm gear fixed to said shaft, a drive shaft provided with a worm in mesh with said worm gear, a manually-operable member usually in the form of a lever, and pawl and ratchet 95 mechanism operable by the movement of said member for transmitting the motion thereof intermittently to said drive shaft. Obviously, the operating member or lever is adapted to be worked back and forth by the workman without undue effort, but the movement of said member or lever in one direction transmits the motion to the drive shaft, the intermittent rotation of which is 100 in one direction only, the power applied to the lever being multiplied by the worm gear. 105

ing between the drive shaft and the tension head shaft, as a result of which the tension head is rotated in a manner to place such tension on the wire binder as to embed said 5 wire in the corners of the package.

Other functions and advantages of the invention will appear from the following description taken in connection with the drawings, wherein:—

10 Figure 1 is a plan view of the machine showing it resting upon a package and with a binding wire applied to said machine and the package in readiness for tensioning.

15 Figure 2 is an elevation of the machine looking toward the left in Figure 1.

Figures 3 and 4 are vertical cross sectional views, partly in elevation, taken in the planes indicated by the dotted lines 3—3 and 4—4, respectively, of Figure 1 looking 20 in the direction of the arrows.

Figure 4^a is a detail sectional elevation of the pawl and ratchet mechanism, on the lines 4^a—4^a of Figure 1.

Figure 5 is an elevation of the retaining 25 member for anchoring a shouldered wire in fixed relation to the machine, said retaining member being releasable quickly for making free the anchored end portion of said shouldered wire.

20 Figure 6 is a detail horizontal section, illustrating the twister, the plane of the section being indicated by the dotted line 6—6 of Figure 5.

Figure 7 is another horizontal section, on 25 the line 7—7 of Figure 5, showing one form of latch for the releasable wire retainer shown in Figures 5 and 8.

Figure 8 is an elevation similar to Figure 5, illustrating the wire retainer in an open 30 position for quickly releasing the shouldered wire after tensioning and securing said wire.

Figure 9 is a detail view of the shouldered wire with the end portions thereof twisted and locked.

45 In the machine shown in the drawings provision is made for supporting the wire tensioning mechanism and the wire twisting mechanism by a suitable frame. In the present example, this frame is in two parts or 50 members, one of which carries the tensioning mechanism and the other of which parts carries the twisting mechanism, but obviously this construction of the frame is a matter of detail capable of variation within wide 55 limits by a skilled constructor.

The frame part A for the twister mechanism includes a base, *a*, and a housing, *a'* for a suitable gear *b*, to impart movement to the twister B. Said base *a* extends forwardly, 60 as at *a²*, beyond the housing, and in said housing is a horizontal slot or recess *c*, the top surface of said extension, *a²*, sloping outwardly and downwardly from said recess, *c*, in order to provide a guiding surface on 65 which the wire may rest and upon which it

may slide so as to facilitate the introduction of said wire into the recess, *c*, and into certain other parts of the machine.

Twister B is shown as having a radial slot, *b'*, and a series of teeth, *b²*, constituting a 70 gear in mesh with the teeth of gear *b*, said twister being provided with a hub, *b³*, extending beyond the gear, *b²*, whereby said twister is adapted to be journaled in suitable bearings provided for the mounting thereof 75 within the housing *a'*, the relation of said twister to the base, *a*, being such that the slot, *b'*, of the twister is adapted to align or register with the recess, *c*, of the housing.

The machine of this invention is useful, 80 more particularly, in connection with a specified kind of preformed wire, the latter being cut to a length suitable to pass around the package to be wired, and said wire being de-

formed to adopt it for insertion into the 85 machine with facility, with a view to effecting saving of time and labor. To this end, we provide means for retaining the pre-

formed wire for one end portion of said wire to be held or anchored in a fixed relation to 90 the machine, the remainder of said wire in the subsequent operation of passing it around the package being free until its other end portion is positioned by the operator

into engagement with a twister and with a 95 rotary head, the latter constituting one element of the tensioning means, another element of which tensioning means is the re-

taining means adapted for holding or anchoring the deformed end portion of the 100 binding wire. This wire tensioning means does not mechanically grip the deformed end

portion of the wire in the sense that said retainer is characterized by moving parts 105 operable, either manually or automatically, for a clamping or gripping effect upon the wire, but, on the contrary, said retaining means is so formed as to cooperate with a shoulder provided on the wire by the de-

formation thereof, as a result of which the 110 retaining means and the deformation of the wire mutually contribute to the result of holding the wire against endwise slipping during the operations of tensioning, or ten-

sioning and locking, said wire. A very con- 115 siderable tension is imparted to the wire, with a view to adapting said wire to serve the functions of a binder and to retain said wire against slipping off the package in the event that the wood shrinks to such an extent

as to loosen the wire, more or less around the package, and such relatively high tension in the wire draws the shoulder thereon into wedging engagement with the retaining 110 means, thus rendering more or less difficult the operation of dislodging the shouldered portion of the wire from the retaining means subsequently to the tensioning and twisting of said wire.

To obviate this objection, provision is made for releasing the shouldered 115

portion of the wire from the retaining means subsequently to the tensioning and twisting of said wire.

120 To obviate this objection, provision is made for releasing the shouldered portion of the wire from the retaining means subsequently to the tensioning and twisting of said wire.

125 To obviate this objection, provision is made for releasing the shouldered portion of the wire from the retaining means subsequently to the tensioning and twisting of said wire.

130 To obviate this objection, provision is made for releasing the shouldered portion of the wire from the retaining means subsequently to the tensioning and twisting of said wire.

wire from the retaining means, and accordingly said retaining means is constructed in a novel manner for the expeditious release of the shouldered wire subsequently to tensioning and twisting the same.

The retaining means is shown more particularly in Figures 5, 7, and 8, as embodying a two-part plate, the members of which are indicated at D, D'. In its entirety, the 10 plate is provided with a slot d for receiving the deformed angular portion of a shouldered wire, and the entrance to this slot is by way of a slot, d', extending to and through the edge of the plate, the edges or 15 walls of the slot d' being relatively inclined to produce a tapering throat into and through which the deformed portion of the wire is passed. Intermediate the slots, d, d', the opposing edges of the members D, 20 D', composing the retaining plate are recessed at d² for the reception of a round portion of wire, as will presently appear. One member of the plate is fixed and the 25 other is movable with reference to the fixed member; as shown, the lower member D is fixed, being fastened to the side of the base, a, by screws e, e, whereas the upper member is movable, being pivoted to the base, a, by a substantial screw e', although the 30 two members D, D', of said plate may be hingedly connected together as at e² in Figure 8. It is preferred to employ a spring as E for normally depressing the movable member D' toward the fixed member D, 35 said spring being shown as being fixedly attached at e³ to a part of the base or housing and positioned for the free end of the spring to act upon the unconfined end portion of the hinged plate member D', see 40 Figures 5 and 8. For locking the hinged member D' in immovable relation to the fixed member D during the operation of tensioning and twisting the wire, and to thus adapt the wire retaining means for efficient service in holding the shouldered wire from slipping relatively to the retaining means, it is advisable to use a latch mechanism of one form or another. One 45 form of latch is shown in Figures 5 and 8, as a bolt F slidably and rotatably supported in the movable plate member D', near the free end thereof, said latch bolt being adapted in the operative position of the 50 plate member D' to enter a socket, f, provided in the base, a. The latch bolt is impelled by a spring, f', into the socket f when the plate member D' is in a closed operative relation to the complementary plate member 55 D, but when the bolt is withdrawn from the socket f, it may be rotated so as to position the stud or pin f² on said bolt out of register with a notch f³, thus holding the bolt in a retracted position when the plate member D' is raised and during the period that

the workman is engaged in manipulating the wire to introduce it into the machine, or while the machine is being removed from the wire and the package.

It will be understood that the latch bolt F is disengaged and plate member D' is lifted by one hand of the operator when the deformed portion x of the wire is slipped through slot c of the base and slot d' of the retainer so that said deformed part x of the wire will be received within the slot d of the two-part retainer, in a position for a shoulder x' of said wire to have abutting contact with an edge of slot d, see Figure 6, whereupon the plate member D' is pressed down by spring E and it is locked by latch bolt F entering the socket f, thus anchoring the shouldered wire in a fixed relation to the machine by the retaining means D, D'. The anchored wire is passed into slot c of base a and slot b' of the twister, then through a slot g of another plate G fixed to the base a on the opposite side thereof from the two-part retainer D, D', then passed around the package, and the otherwise free end of such wire is then engaged in the notched edges d² of the two-part retainer, then passed again within the slot b' of the twister and the slot g of the plate G, and finally the otherwise free end of said wire is engaged with a rotary head H of the tensioning means. It will be noticed that the wire is positioned for two lengths thereof to lie in parallel relation to each other and within the slotted plates, D, D', G, and slotted twister, B, the deformed end of said wire being held or anchored by one plate, D, D', whereas its other end is attached to head H. The slots in the plates D, D', and G, confine the two parallel portions of the wire against turning with reference one to the other during the rotation of twister, B, and as the outer one of the two parallel lengths of wire is engaged by the notched edges, d², of the two-part retainer, D, D', said wire is precluded from slipping out of engagement with said retainer when the twister is rotated for twisting together said end portions of the wire, as at x² in Figure 9. It should be stated that the width of the slot, g, in the fixed plate, G, is a trifle larger than the diameter of the wire, so that the wire can be freely entered and withdrawn, but the slotted plate in conjunction with the two-part slotted retainer serves to preclude movement of the two parallel lengths of wire at the time the twister is rotated.

The tension mechanism, except for the two-part retainer, D, D', is carried by one member, I, of the two-part frame, the other part A of which is the base a and housing a'. This frame member, I, as shown, comprises a base, i, and upright members, i', unitary

with said base, *i*, said frame member, *I*, being provided with rods, *i*², which extend from one side of the frame part, *I*, and are received in suitable openings (not shown) 5 of the frame part, *A*, whereby the rods, *i*², couple the two frame parts, *A*, *I*, so as to keep them in fixed positions relatively to each other. If desired, one of the coupling rods, *i*², may be extended through, and for 10 a distance beyond, the frame part, *A*, as shown in Figure 1, so as to receive a coiled spring, *I'*, acting against a collar, *i*³, for yieldably drawing the two frame parts, *A*, *I*, for the bases, *a*, *i*, thereof to have abutting 15 contact, but this spring may be omitted, if desired, and the rod, *i*², be pinned or otherwise made fast to the frame part, *A*, for rigidly coupling the two frame members.

By making the support in two parts, *A*, *I*, the twisting means and the tension means may be made and assembled separately, the separate assemblage being desirable in some respects from a manufacturing standpoint, but this mechanical detail may be 20 modified by a skilled constructor. In suitable bearings on the uprights, *i*, of the frame part, *I*, are journaled two shafts, *J*, *K*, positioned at a right angle one to the other, one shaft being above the other shaft. The 25 upper shaft, *J*, of the said two shafts, is provided with a worm, *j*, whereas the lower shaft, *K*, is provided with a worm gear, *k*, in mesh with said worm, *j*. Said upper shaft, *J*, acts as the driving or power shaft, 30 and it is provided, also, with a ratchet, *L*. Loosely fitted on the power shaft is a hand lever, *L'*, arranged in a convenient position for operation by the workman. Said lever turns freely on the power shaft for movement 35 in an arc, of which the shaft is the axis, and the stroke of the lever in one direction is communicated by a feed pawl, *l*, to the ratchet, *L*. The lever is worked back and forth by a minimum of effort on the 40 part of the workman, to effect the rotation of the worm shaft intermittently and in one direction, the backward turning of the worm shaft under the pull of the wire, to which tension is applied, being precluded by the 45 friction between the worm gear and the worm, and such backward turning of said worm shaft being positively arrested by a check pawl, *l'*, hung on one of the uprights, *i*, and engaging with a tooth of the ratchet, *L*, see Figure 4^a. The shaft, *K*, protrudes 50 at the end from frame part, *I*, into an overhanging relation to the position assumed by the wire when introduced into the machine, and on this protruding end of said shaft is fixedly secured the rotary tension head, *H*. In the form of this head shown in the 55 drawings, it comprises a member, *h*, in the form of a disk, and a plurality of studs, *h'*, said studs being spaced equidistantly from each other and being unitary with said disk.

The studs project from one face of the disk, see Figure 4, and are spaced for distances which permit an end portion of the wire *X* to be easily placed against a face of the disk and bent with reference to two or more 70 of said studs, as depicted in Figure 2. The studs are of angular formation in cross section, see Figure 2, to present sharp edges which, under the pull or strain of the wire, will bite into said wire at the points at 75 which the wire is bent into contact with said angular corners of the studs, as a result of which the wire is put under tension by the rotary motion of the head, and said wire, due to the angular formation of the studs 80 and the relation of said studs, is held in a practical manner and by frictional engagement into the required connection with, or attachment to, the tension head, *H*, without resorting to clutches or grippers for effecting the fixed attachment of the wire to a moving part. The tension head is positioned adjacent the plate, *G*, through which the wire passes, and said head turns on an axis at a right angle to the axis of movement 85 of the hand lever, *L'*. Said hand lever is rocked back and forth with an easy motion by the operator for intermittently turning the tension head, but the power transmitting worm and the worm gear act to increase 90 the effort, or multiply the power, of the lever in a manner to apply very considerable strain to the wire for placing it under such tension as to embed said wire into the 95 corners of the package.

Referring now to the twister, *B*, it is horizontally positioned within a portion of housing *a'*, and a portion of base, *a*, the tooth formed surface, *b*², of said twister extending into a marginal part of said housing. In a normal position, the slot, *b*', is in alignment or registers horizontally with the slot, *c*, of the housing and with slots, *d*, *d'*, of the plate, *D*, *D'*, and slot, *g*, of plate, *G*, thus enabling the binding wire to be slipped easily into position. The toothed surface, *b*², constituting the twister gear is in mesh with the teeth of power gear, *b*, the latter being provided with a shaft, *b*³, and with an operating handle, *B'*. The shaft *b*³, protrudes at one end beyond the housing, *a'*, and to it is fixedly secured a cam arm, *M*, the latter being adapted to strike the cutter lever, *N*, positioned in the path of said cam arm. As shown in Figures 2 and 3, the cutter lever occupies a vertical position alongside the slotted plate, *G*, fixed to one side of the base, *a*, and adjacent to the housing, *a'*, said cutter lever being fulcrumed at its lower end by a screw or stud, *n*, fixed to the base, *a*. A spring *m* is connected to the cutter lever for holding it in a normal position in the path of cam, *M*, and the movement of said cutter lever under the action of the spring is arrested by a stop, *m'*, posi- 110 115 120 125 130

tioned on said lever to strike against base, *a*, see Figures 1 and 3. The lower part of the cutter lever adjacent the fulcrum stud, *n*, is provided with a notch, *o*, and fashioned to produce a cutting edge, *p*, whereby in the normal position of said cutter lever its lower portion is in overhanging relation to the parallel strands of the wire, one strand being substantially in the vertical plane of the notch, *o*, whereas the other strand is directed below the cutting edge, *p*, as clearly shown in Figure 3. The cam is so timed with reference to the twister that after the wire shall have been twisted, as at *x²*, the cam strikes the cutter lever and rocks it on the pivot, *n*, thus moving the lever for the cutting edge, *p*, to sever that strand or length of wire leading from plate, *G*, to the tension head, *H*. The cutter is in shearing relation to the plate, *G*, and said cutter severs the wire close to one of the twists, *x²*, in said wire, leaving no free or protruding wire ends to catch into packages or injure the hands of the workmen who are required to handle the packages bound with this wire.

As shown in Figures 1, 2, and 4, the angular studs, *h'*, of the rotary tension head are each headed, at *h²*, said head being provided on the stud at the outer end thereof, and to leave a space between the head and the face of the disk, *h*, into which space the wire is placed, the heads, *h²*, of the studs operating to limit the movement of the wire away from the face of the head in the adjustment of said wire, while it is free or slack, into operative contact with the tension head and at the initial stage of placing tension on said wire when movement is first imparted to the tension head. The tension head is rotated intermittently by the rocking movement of the power lever, *L'*, transmitted through the power-transmitting worm and worm gear, said tension head being rotated a required number of times for taking up the slack in the wire so as to draw it into contact with the surfaces and corners of the package, and the rotation of said tension head being continued indefinitely until the wire is wound, more or less, upon the studs of said head, for placing tension upon the wire to the required extent, or until the wire is drawn so tightly around and into contact with the package as to become embedded into the corners of said package and to, in effect, compress or bind the package tightly, and thus compensate for shrinkage in the wood composing the package.

In fact, there is no limit to the action of the rotary head in the operation of placing tension on the wire, even to straining the wire to the breaking point, such unlimited action of the tension head being quite desirable in placing tension on wires which may vary in length to suit packages of different sizes, and, furthermore, the use of a rotatable

head operated by a pawl and ratchet mechanism allows the machine to be placed in any appropriate position relatively to the package of small or large dimensions.

The operation will in a measure be apparent from the foregoing description, but may be summarized, as follows: The machine is placed upon a package and a preformed wire of a length suited to the package is selected or taken from a bundle of such wires, the deformed part, *x*, of the selected wire being slipped into slot, *d'*, so as to be received finally within the slot, *d*, within which the deformation, *x*, of the wire is snugly received, with the shoulder, *x'*, of said wire in abutting contact with the retainer, *D*, *D'*. The introduction of the deformed portion of the wire with the retaining means is facilitated by lifting the member, *D'*, of said retainer, thus placing the spring under tension, and the reaction of this spring depresses the member, *D'*, relatively to the member, *D*, and the inserted wire, although at this initial stage of positioning the wire within the machine, it is not required to lock the retainer member, *D'*, by the bolt, *F*. The wire passes from the retaining means into the slot, *c*, of the frame, the slot, *b'*, of the twister, and slot, *g*, of retainer plate, *G*, said wire being passed below cutter, *N*, and tension head, *H*, and said wire being passed around the package, for the free or unconfined end thereof to be manipulated as follows: The retainer member, *D'*, is raised slightly for said free end to be slipped into the notch, *d²*, of the retainer, whereupon the member, *D'*, is pressed back into position and locked in fixed position by the latch bolt, *F*, entering the socket, *f*, thus confining both strands or lengths of the wire within the retainer, *D*, *D'*; said free end is again passed through the twister, *B*, and plate, *G*, below the cutting edge, *p*, of the cutter lever, *N*, and finally the free end portion of the wire is passed between certain of the angular studs, *h'*, and into contact with the sharp corners of other studs, *h'*, on the rotary head, substantially as indicated in Figure 2. Said end of the wire in contact with the studs of the tension head is held temporarily by hand, whereas the power lever, *L'*, is operated one or more times so as to turn the head, *H*, sufficiently for the wire to be strained, thus connecting the wire to the studs of the head, whereupon the hand is removed from the wire and the lever, *L'*, thereupon operated the required number of times to turn the head sufficiently for winding the wire around the studs. The power lever in conjunction with the ratchet mechanism and the power transmitting worm and the worm gear affords a simple powerful mechanism, capable of operation without undue effort on the part

of the workman for placing tension to the desired extent upon the wire, one end of which is in effect anchored against slipping by the two-part retainer, D, D', and the other end of which is connected with the head so as to be wound thereon upon the rotation thereof, two of the strands or lengths of the wire being confined in parallel order within the slot of the twister by the retainer, D, D', and the plate, G, the slots in which retainer, D, D', and plate, G, preclude the wire lengths or strands from turning one around the other at the points of grasp, by said parts, D, D', and G, when the twister is rotated.

The wire having been placed under the required tension by the rotation of the tension head for an indefinite number of times, the operator then turns the lever, B', by pulling it toward the front of the machine, the result of which is to impart motion to gear, b, and twister, B, whereby the wire is twisted together at x^2 in Figure 9, the deformed part, x, and one strand of said wire being held in D, D', and the two strands being held in the slot, g, of plate, G, so as to preclude rotation of the two said strands at the specified points of grasp, whereby the wire end portions are twisted or intertwined and thus securely locked or fastened together. As the twister completes its operation, the cam, M, impinges cutter lever, N, and rocks the latter for the edge, p, to cut one strand of the wire at a point close to one of the twists, x^2 , thus severing that length of wire connected to tension head, H, from which the cut wire is readily detached. The latch, F, is now released and retainer member, D', lifted with respect to the complementary retainer member, D, thereby releasing the deformed portion, x, and shoulder, x' , of the wire from the retainer, D, D', and the machine is now slipped easily and quickly away from the applied wire. The lever, B', is returned to a normal position, so as to restore the twister to a position in register with the slots in the retainer, D, D', and G, but is not required to restore the tension head, H, nor its power lever, L', to a given position, the implement being in readiness for operation upon another binding wire.

The tension head is rotated intermittently by the action of the power lever and the pawl and ratchet mechanism, movement being imparted to said head upon the stroke of the lever, L', in one direction, but on the reverse movement of the power lever, no slackening of the wire can take place, due to the cessation of the power stroke of said lever, L', for the reason that the worm gear in mesh with the worm precludes any relaxation of the strain previously applied to the wire, and such relaxation of strain is precluded in a positive manner by the check pawl, l', in engagement with ratchet,

L, as a result of which the strain of the wire under partial or complete tension cannot, during the reverse or idle movement of the power lever, L', turn the head, H, or ratchet, L, in a reverse direction, whereby the tension head is rotated continuously in one direction by the operation of the power lever and any reverse rotation of the tension head is precluded by the worm and worm gear and by the pawl and ratchet mechanism.

As shown, the base, a, of the frame part, A, is provided with a post A' rearwardly of the housing, a', said post being unitary with the rearward part, a', and having a head, a'', upon which pressure may be applied to hold the machine from movement during the operations of tensioning and twisting the wire.

Having thus fully described the invention, what we claim as new and desire to secure by Letters Patent is:

1. In a machine of the class described, wire-retaining means embodying a plurality of complementary parts slotted to correspond with a deformation of a wire adapted to be held against slipping and recessed to receive and retain a length of said wire into parallel relation to that length which is held by the slotted parts, one of said parts being shiftable for effecting the release of said wire held by said retaining means.

2. In a machine of the class described, wire retaining means embodying a plurality of complementary parts slotted for the ready insertion of a previously deformed wire, one of said parts being mounted on a pivot parallel with the wire and shiftable for releasing said wire, and a spring member acting on the shiftable part to hold it in cooperative relation to another of said parts.

3. In a machine of the class described, wire-retaining means embodying a plurality of complementary parts slotted for the ready insertion of a previously deformed wire, one of said parts being mounted on a pivot parallel with the wire and shiftable for releasing said wire, and means for locking said shiftable part in a fixed relation to the other of said parts.

4. In a machine of the class described, wire-tensioning means embodying worm-gear means for putting wire under tension, a separable retaining means cooperable therewith constructed to grasp a wire previously deformed at a distance from its end, the last named means being separable at will to permit disengagement of the wire.

5. In a machine of the class described, a wire-retaining member embodying a plurality of complementary parts slotted for the reception of a wire previously deformed at a distance from its end, one of said parts being on a pivot parallel with the wire for

movement relatively to the other of said parts, and means for confining said hinged part in fixed relation to the other part.

6. In a machine of the class described, 5 a frame, a twister member rotatably mounted therein, a recessed wire-retaining member carried by said frame for anchoring a deformed portion of a previously deformed wire on said frame, said recessed member being composed of complementary parts movable relatively for effecting the release of said deformed wire, and a rotatable worm-gear operated tension head in cooperative relation to the wire-retaining 15 and releasing member, said latter member being operable at will and independently of said tension head for releasing said deformation of the wire and facilitating the dislodgment thereof against that tendency 20 to become wedged in said member when tension is placed on said wire by the rotation of said head.

7. In a machine of the class described a multiple-part retaining means having 25 vision for receiving between such parts a wire previously deformed at a distance from its end, one of said parts being mounted on a pivot parallel with the wire and resiliently held and separable to release the wire after 30 it has been tensioned.

8. In a machine of the class described, a frame provided with a wire receiving slot, and a retaining member disposed at an angle to said wire receiving slot, said member being composed of a plurality of parts 35 recessed to receive the deformation of a previously deformed wire and one of said parts being spring-pressed and movable on a pivot parallel with the said wire.

40 9. In a machine of the class described, a frame provided with a wire-receiving slot, a wire-retaining member composed of a plurality of complementary parts recessed for engagement with a deformation of a 45 previously deformed wire, one of said parts being mounted on a pivot parallel with the wire, the parts of said wire-retaining member being relatively separable for quickly releasing said wire, and tensioning means 50 engageable with another part of said wire.

55 10. In an implement of the character described, a wire binder retaining means comprising two movably united members one of said members being spring-pressed and the opposed faces of which are formed to receive the deformed portion of a previously deformed wire and to constitute the sole means of anchoring said wire when the latter is put under tension, said members being 60 mounted on a pivot parallel with the wire.

11. In an implement of the character described, a wire binder retaining means comprising a plurality of complementary members, one of which is pivotally connected

with another and spring-pressed, the opposed faces of said members having a conformation corresponding to that of a deformed portion of a previously deformed wire to form an abutment to and serving as the sole anchoring means to prevent endwise movement of the wire when tensioned in the direction of its length, and means carried by the movable member for locking it in closed relation to the other member.

65 12. In a machine of the class described, means conforming to the deformation of a previously-deformed wire and serving solely as the anchorage for one end of such wire and separable to release the wire, said means being composed of a plurality of parts a 70 tension head provided with means for holding the other end of the wire, a power member for intermittently rotating the tension head, a worm and worm gear intermediate the power member and the tension 75 head constructed to rotate the latter in one direction and to lock the same against movement in the opposite direction.

80 13. In a machine of the class described, a wire-tensioning means including a member for placing tension on a wire, and a second member for anchoring an end portion of said wire, said second member conforming to and grasping the deformation 85 of a previously-deformed wire and said second member being separable at will for releasing the wire after tensioning said second member being spring-pressed.

90 14. In a machine of the class described, a frame provided with a wire receiving slot, 100 and a wire retaining member composed of a plurality of parts each provided with a recess adapted to register with the other recess and co-operable therewith for receiving the deformation of a previously deformed wire for retaining said wire against 105 movement under tensional strain, said parts being separable for releasing said deformed wire.

110 15. In a machine of the class described, a frame provided with a wire receiving slot, and a wire retaining member composed of complementary parts recessed for engagement with the deformation of a previously deformed wire, said parts being separable 115 for releasing said deformed wire and said parts being relatively positioned to receive a round portion of the wire adjacent to said recess.

120 16. In a machine of the class described, a retaining member composed of opposed complementary parts relatively movable and provided in their adjacent faces with notches to receive the normal shaped portion of a wire and with depressions to receive an 125 abnormal formation of the wire.

17. In a machine of the class described, a retaining member composed of opposed

complementary parts relatively movable and provided with opposed notches to receive the normal shaped portion of a wire and depressions to receive an abnormal formation of the wire, said depressions and notches being positioned adjacent each other and at right angles to the length of the wire.

In testimony that we claim the foregoing as our invention, we have hereunto signed our names at the city of New York, borough of Brooklyn, this 29th day of September, 1922.

VINCENT RAGONA.
JOSEPH H. McFAUL.
